UNITED STATES PATENT OFFICE

STANLEY H. DURBIN, OF HUDSON, NEW YORK, ASSIGNOR TO GIFFORD-WOOD COMPANY,
OF HUDSON, NEW YORK, A CORPORATION OF NEW YORK

TROLLEY BUCKET

Application filed March 19, 1931. Serial No. 523,886.

This invention relates to trolley buckets, that is, traversing hoist buckets which receive their loads from above and discharge the same through their bottoms; and among other objects, aims to provide a bucket controlled entirely by the hoist line, as shown in the Bennett Patent No. 1,741,123, December 24, 1929, which, however, is advantageously closed automatically as soon as the load is discharged, thus effecting important economies in the construction of the plant and improving operating conditions.

In the accompanying drawings of a preferred embodiment of the invention,—

15 Fig. 1 is a side elevation of the bucket;
Fig. 2 is an end elevation of the bucket;
Fig. 3 is a side elevation, showing the bucket open; and

20 Fig. 4 is a sectional elevation on an enlarged scale showing details of the construction.

In accordance with the invention, and as shown in the drawings, I provide a bucket comprising a "split" or two-part body, suspended from a pivoted bail which is supported by a power-actuated hoist line (not shown). The bucket body consists of two similar halves 10, 11, each comprising side walls 12, end walls 13 and a sloping bottom 14, pivotally connected together adjacent their tops by axially aligned pivot pins 15. Each side wall 12 has fenders 16, 17 projecting above the top and below the bottom thereof, as fully described and claimed in 25 Bennett Patent No. 1,791,882 dated February 10, 1931, and also has strengthening ribs 18, 19 on the outside thereof. The vertical meeting edges of the bucket halves 10, 11 are stiffened by straps 20, while the contacting 30 edges of bottoms 14 are similarly strengthened by angles 21.

To hold the bucket halves in closed position, so that the bucket may carry a load, one or more latches 22 are provided, said latch or latches being secured to a rock shaft 23 journaled in bearings 24 on the bottom of one of the bucket halves. Each latch 22 may have a roller 25 on its free end, and engages with a keeper 26 projecting from and preferably formed from an extension of one of

the angles 21. To trip the latches, one or more trip pads 27 is provided, each trip pad being fast to the rock shaft 23 to rock the same to lift the latch or latches whenever the bucket descends low enough to bring said trip pads into contact with an obstacle, such as the bottom of a bin, or the top of a pile of material. Similar bucket-latching means are shown in the above mentioned Bennett patents; but obviously any form of bucket locking or latching mechanism, which is released or tripped upon contact with the ground, may be employed with the present bucket.

The bail by which the bucket is suspended 65 comprises two arms 28 and a cross bar 29, a sheave 30 for the hoist cable being pivotally mounted on top of cross bar 29. As shown in Fig. 4, the lower ends of arms 28 are pivoted on the pivot pins 15. A roller 31 is 70 rotatably mounted on each pin 15, as shown, and the two rollers 31 provide means (co-operating with tracks, not shown) by which the bucket is guided as it rises and descends from the loading point. See Patent No. 75 1,791,844 dated February 10, 1931, for example. It will be observed that whereas the two aforesaid Bennett patents show two guiding rollers on each side of the bucket, the present bucket has but one roller on each side, 80 thus effecting an economy in manufacture and also making the bucket lighter in weight. It is possible to employ but one pair of rollers on the present bucket because it is used with a novel form of automatic gate which is the 85 subject-matter of a copending application, Serial No. 580,707 filed by me December 12, 1931.

The present bucket is designed to open and close automatically, as will now be described, when lowered and hoisted by the hoist line. The two halves of the bucket are not directly pivoted on the pivot pins 15 but are connected thereto by plates 32, 33, the plates 32 being outside of the side walls 12 and the plates 33 being inside. Pivots 34, 35 pass through plates 32, 33 adjacent their lower edges and at the opposite ends thereof, and also pass through the side walls 12 so as to unite the bucket halves to said plates. The 90 95 100

5 pivot pins 15 also pass through the spaced plates 32, 33 as clearly shown in Fig. 4; and as the bail is connected to said pins 15, it follows that the bucket is supported 10 through the plates 32, 33 and that the bucket halves may swing on the respective pivots 34, 35 when the bucket is suspended from the bail. To cause simultaneous action of the bucket halves, when opening and closing, 15 links 36 are pivotally connected as at 37, 38 to the bucket sides 12 on each side of the body. The links 36 are preferably adjustable in length, as clearly shown in Fig. 3, to insure proper action.

15

Operation

Assuming the bucket to be closed and latched, as in Fig. 1, and full or partly full of material, the bucket is elevated by the 20 hoist line (and in the case of a trolley bucket system is then moved horizontally by a traverse line) and then lowered to the point where its contents are to be dumped. As soon as one or more of the trip pads is rocked 25 by contact with the ground, or with the top of a pile of material, the latch is tripped to permit the bucket to open. The weight of the material in the bucket presses against the downwardly inclined bottom sections 14, and 30 thus there is a component of force tending to move the two bucket sections apart. The full line position of Fig. 3 is only momentarily assumed, however, and may be considered the full discharge position, assumed 35 when a heavy load is rapidly discharged from the bucket. The initial position of the bucket sections when dumping is approximately the one indicated in dotted lines in Fig. 3; and said dotted line position is also 40 substantially illustrative of the bucket when the flow of material has nearly ceased; and just before the hoist line starts to hoist the bucket again.

As soon as the hoist line, upon first being 45 hauled in, supports the entire weight of the bucket, the bucket halves close, because the center of gravity of each half is between the pivots 34, 35, and of course is lower than the line joining said pivots. The mass of the 50 bucket halves is such as to bring them together with some force, so that the latches are automatically engaged to maintain the bucket closed during the remainder of the operating cycle. Thus it is seen that the 55 bucket descends to the loading point with its bottom closed. This is advantageous not only in eliminating bottom-closing members (as disclosed in the Bennett Patent No. 1,741,128) but what is more important, permits the use of a shallower pit or pocket for 60 the bucket to descend in. A saving of eight inches or more in a concrete pit effects a saving in materials and labor and hence in cost of installation, and incidentally saves wear 65 and tear on the bucket. Furthermore, to

have the bucket descend with its bottom closed is in an insurance against spillage of coal, or other material caught in cracks or joints in the bucket, such material being a serious annoyance as it accumulates in the 70 pit and must be removed from time to time by hand. Finally, as previously stated, the bucket is simplified and made lighter in weight, because of the elimination of one pair of rollers, and also because a fender or 75 bumper on the bottom for striking a bottom-closing abutment is no longer necessary.

Obviously, the present invention is not restricted to the particular embodiment thereof herein shown and described.

What I claim is:

1. A bucket comprising two complementary sections together making up the body of the bucket and each having two side walls, an end wall and a sloping bottom; a pair of spaced plates on each side of the bucket having pivotal members at the opposite ends; the bucket sections having their side walls between the two plates of each pair and being pivotally supported by the aforesaid pivotal members; a bail attached to said plates for supporting the bucket; and obstruction-tripped latching means for holding the bucket sections in closed position.

2. A bucket comprising two complementary sections together making up the body of the bucket and each having two side walls, an end wall and a sloping bottom; a pair of spaced plates on each side of the bucket having pivotal members at the opposite ends; the bucket sections having their side walls between the two plates of each pair and being pivotally supported by the aforesaid pivotal members; a link pivotally connected to the side walls of the two bucket sections on each side of the bucket; a bail attached to said plates for supporting the bucket; and obstruction-tripped latching means for holding the bucket sections in closed position.

3. A bucket comprising two complementary sections together making up the body of the bucket and each having two side walls, an end wall and a sloping bottom; a pair of spaced plates on each side of the bucket having pivotal members at the opposite ends; the bucket sections having their side walls between the two plates of each pair and being pivotally supported by the aforesaid pivotal members; a bail pivotally attached to the two pairs of plates on opposite sides of the bucket; and a latch, tripped by contact with an obstruction encountered beneath the bucket, for holding the bucket sections in closed position.

4. A bucket comprising two complementary sections together making up the body of the bucket and each having two side walls, an end wall and a sloping bottom; a pair of spaced plates on each side of the bucket having pivotal members at the opposite ends; the

bucket sections having their side walls between the two plates of each pair and being pivotally supported by the aforesaid pivotal members; a bail pivotally attached to the 5 two pairs of plates on opposite sides of the bucket; a roller rotatably mounted on each side of the bucket outside said pairs of plates, the roller axis substantially coinciding with the axis about which the bail may swing relative to the bucket; and a latch, tripped by 10 contact with an obstruction encountered beneath the bucket, for holding the bucket sections in closed position.

5. A bucket comprising two complementary 15 sections together making up the body of the bucket and each having two side walls, an end wall and a sloping bottom; means from which the bucket sections depend and on which the bucket sections may swing; the pivots of the 20 bucket sections being spaced apart; a bail pivotally attached to the aforesaid means, so that the bucket may be supported by the bail; a roller rotatably mounted on each side of the bucket; the axis of said rollers substantially coinciding with the axis about which the bail may swing relative to the bucket; the bail being swingable between the rollers; a link on each side of the bucket pivotally connected at each end to the side walls of the 25 bucket, said links extending each at an acute angle to lines joining the pivots of the bucket sections, one pivotal connection of each link being near the top of the bucket, the other pivotal connection being below said line 30 and at an intermediate part of the bucket; and a latch, tripped by contact with an obstruction encountered beneath the bucket, for holding the bucket sections in closed position.

6. A bucket comprising two complementary 40 sections together making up the body of the bucket and each having two side walls, an end wall and a sloping bottom; means from which the bucket sections depend and on which the bucket sections may swing; the pivots of the bucket sections being spaced apart; a bail pivotally attached to the aforesaid means, so that the bucket may be supported by the bail; a roller rotatably mounted on each side of the bucket, the axis of said rollers substantially coinciding with the axis 45 about which the bail may swing relative to the bucket; the bail being swingable between the rollers; means mechanically connecting the two bucket sections together so that they 50 must open and close simultaneously; and a latch, tripped by contact with an obstruction encountered beneath the bucket, for holding the bucket sections in closed position.

In testimony, that I claim the foregoing as 55 my own, I have hereto affixed my signature.

STANLEY H. DURBIN.
